(57) CLAIM

The ornamental design for a four wheels motor vehicle, as shown and described.

DESCRIPTION

FIG. 1 is a front view of a four wheels motor vehicle incorporating our new design;

FIG. 2 is a back view thereof;

FIG. 3 is a right side elevational view thereof;

FIG. 4 is a left side elevational view thereof; and,

FIG. 5 is a top plan view thereof.

The bottom view of the four wheels motor vehicle incorporating our new design is not shown in the drawings and its ornamental design is not part of the claimed design.
